UNITED STATES PATENT OFFICE

MATA IZUMIYA, OF CHAGRIN FALLS, OHIO

PRESSING IRON

Application filed October 17, 1927. Serial No. 226,568.

This invention is an improvement in pressing irons.

An object of my invention is to construct a pressing iron of the type having a self-contained steam generating means, whereby a uniform flow of live steam may be applied directly to the article to be pressed.

Another object of my invention is to construct a sheet metal pressing iron of the above named character which is safe, light, simple of construction, compact and easy to handle.

A further object of my invention is to construct an iron for pressing which will not burn or mark the articles to be pressed.

Other objects and advantages of my invention will become more apparent as the following description of one embodiment thereof progresses, reference being made to the accompanying drawings in which like reference characters are employed to designate like parts throughout the same.

In the drawings:

Fig. 1 is a phantom plan view of the iron forming one embodiment of my invention.

Fig. 2 is a longitudinal section taken on line 2—2 of Fig. 1.

Fig. 3 is a transverse vertical section taken on line 3—3 of Fig. 1.

In the form of my invention illustrated in the accompanying drawings, 1 is the sheet metal body of the pressing iron having a sheet metal bottom plate 2 which is engageable with the article to be pressed. A handle 3, is provided on the upper face of the body 1 and an electric connection receiving socket 4 is provided at the rear end of the body for receiving the insulated plug 5 connected at one end of an electric cable 6, the cable being connected at its other end to a source of electrical energy. A terminal block 7 of suitable insulating material such as porcelain or the like, is provided at the base of the socket 4 and carries the terminals 8 of the electrical heating unit 9. The heating unit 9 is housed within a water proof casing 10 near the bottom face 2 of the iron body and is electrically insulated therefrom by the insulating material 9a. The interior 11 of the body provides a suitable container for a quantity of water, the preferred water line being indicated at

12 in Figs. 2 and 3, but less water may be used if desired.

A plurality of plates or baffles 13 and 13a divide the interior of the body 1 into compartments 14, 15 and 16 respectively, and prevent splashing of the water within the iron while the iron is in use. The plate 13 is cut away as at 17, and the plate 13a is cut away as at 18, to permit the water in one compartment to flow into another compartment so that the water level 12 will be substantially the same in each compartment when the iron is in a horizontal plane as indicated in Fig. 2. The upper walls of the plates 13 and 13a are spaced from the upper iron wall 19 as at 17a and 18a, respectively, to permit the steam to pass from one compartment to another and to equalize the steam pressures therein. Secured to the upper wall 19 of the body 1 is a trap 20, the interior of which communicates with the interior of the compartment 14 by means of an aperture 21 formed in the wall 19 of the body. The trap 20 is preferably a dome like structure and terminates in a conduit or tube 22. A trap plate 21a is secured within the dome 20 and is provided with one or more openings 20a to permit the steam in the lower portion of the dome to pass upwardly into the tube 22, but which prevents any passage of water into the tube. If any of the steam passing into the tube 22 should condense in the portion of the tube outside the iron, it will either pass back into the trap and thence to the water compartment, or down into the vertical portion of the tube which passes through the heated water within the iron, when it may be vaporized again before it passes out of the openings 25. The tube 22 is curved upwardly and then downwardly from the trap entering the chamber 14, and then passes downwardly through the chamber and the heated water therein to a point adjacent the bottom plate 2, where it communicates with the transversely extending steam ducts 23. A transverse recess 24 is formed in the bottom plate 2 and extends directly below and substantially parallel to the ducts 23. A series of small steam ejecting apertures 25 are formed in the recess 24 at intervals extending across the bottom face 110.

of the iron and communicate with the interior of the ducts 23 so that the steam entering these ducts through the tube 22, may be ejected in the series of jets through the small openings 25 onto the article to be pressed. 5 A three way cut off valve 26 may be inserted in the tube line 22 to cut off the supply of steam from the chamber 20 to tube 22, or to exhaust the steam thru outlet port 26a when desired. The valve 26 may be operated to cut off the flow of steam both through the port 26a and through the conduit 22 and ducts 23 simultaneously, or if desired it may be operated to eject a jet of steam through the port 10 26a alone onto an article placed near the said port. In this manner steam from the interior of the iron may be directed through the valve and port directly onto an article to be steamed, such as a hat. In Fig. 3 I have 15 shown a pressure gauge 27 so communicating with the interior of the body 1 so that the pressure of steam generated within the chamber, and which accumulates above the water line, may be indicated. I also provide a safety valve 28 in which the valve head 29 is normally seated on a valve seat 30 by the compression of a spring 31. The compression of the spring 31 may be adjusted to the desired degree by turning the cap 32 which is screw 20 threaded over the body 33. The valve body 33 is threaded at 33a permitting it to be screwed into the falling opening 40. Shoulders 41 are formed on the body 33 to permit the operator to readily screw the valve into the 25 opening 40, without disturbing the adjustment of the valve. If the steam pressure in the interior of the iron exceeds a safe operating limit, the safety valve 28 will be actuated to release the pressure. Water may be introduced into the body of the iron through the 30 filling opening 40 by removing valve 28 therefrom. A water gage 50 is provided to indicate the level of the water within the iron.

In use, the embodiment of my invention 35 illustrated in the accompanying drawings operates as follows:

When the connector 4 is connected with the terminals 8 as shown in Fig. 2 and electric current is supplied to the heating unit 9 the 40 temperature of the water will be raised gradually to a point sufficient to generate steam while the bottom plate 2 will become hot enough to permit the iron to be used for 45 pressing articles. Steam thus generated within the body 1 will be communicated through the opening 21, into the trap 20, passing through the openings 20a of the plate 21a and thence into the tube 22, where it is communicated to the ducts 23 extending 50 transversely of the iron. This steam will then be ejected in the form of jets through the openings 25 to the article over which the iron is passed during the pressing operation, thus eliminating the application of steam by 55 hand or from an exterior source of supply

during the pressing operation. In the operation of my invention it is desirable to maintain the water level above the heating element shown at 10 in Figs. 2 and 3.

It will be seen that I have constructed a 70 pressing iron which is extremely simple in construction, light, safe, easy to handle, compact, and which is extremely efficient in operation.

It will be seen that I have constructed a 75 pressing iron constructed preferably of sheet metal and having a self-contained steam generating and distributing means, permitting the iron to be used for pressing without danger of burning the articles to be pressed, by projecting steam upon the articles while the iron is in contact with the articles to be pressed. This condition will exist as long as steam is ejected onto the articles through 80 the openings 25.

An iron constructed in accordance with 85 this invention may be safely operated over a considerable period without replenishing the water supply. However, the water level should not be allowed to go below the heating unit and for this reason I have provided the gauge 50. It will be noted that the heating unit is preferably located near the presser plate 2 being nearly entirely surrounded by the water within the iron. It will also be 90 noted that by my invention I am enabled to supply a constant flow of steam on to the articles to be pressed, and that the flow may be controlled by the 3-way valve 26.

Having thus described one embodiment of 95 my invention so that others skilled in the art may readily practice the same, what I claim and desire to secure by Letters Patent is defined in the following claims:

1. In a self contained steam generating 100 pressing iron, in combination, a water reservoir, a steam dome thereabove, a steam pipe leading from said dome to the pressing face of said iron, and baffles in said reservoir and said dome to prevent passage of water into 105 said pipe.

2. In a steaming and pressing iron adapted 110 to apply steam to the article being pressed, a hollow body comprising a water reservoir, a pressing face therebeneath, a heater in said reservoir adapted to heat said water for the purpose of generating steam and also of heating said face, a steam conduit from the upper part of said reservoir to said face, and baffle plates in said reservoir to prevent 115 splashing of water into said conduit.

3. Means for steaming and pressing fabrics comprising a boiler, a pressing face constituting the bottom of said boiler, a steam delivery pipe from said boiler, a steam connection from said pipe to said pressing face, an outlet from said pipe above said boiler, and a valve having a plurality of outlets in 120 said pipe, one of said outlets having a conduit extending to said pressing face, another 125

of said outlets communicating with the atmosphere, means for closing or opening said outlets whereby steam may be selectively directed either to said connection extending to said pressing face or to said outlet and exhaustion therefrom, or shut off entirely from communication with either.

In testimony whereof I hereunto affix my signature this 13th day of October, 1927.
